UNITED STATES PATENT OFFICE.

ROBERT M. DIXON, OF EAST ORANGE, NEW JERSEY, ASSIGNOR TO THE SAFETY CAR HEATING & LIGHTING COMPANY, A CORPORATION OF NEW JERSEY.

ACETYLENE-GAS BUOY.

No. 926,475.

Specification of Letters Patent.

Patented June 29, 1909.

Application filed June 6, 1908. Serial No. 437,074.

To all whom it may concern:

Be it known that I, ROBERT M. DIXON, a citizen of the United States, residing at East Orange, in the county of Essex and State of New Jersey, have invented certain new and useful Improvements in Acetylene - Gas Buoys, of which the following is a full, clear, and exact description, such as will enable others skilled in the art to which it appertains to make and use the same.

This invention relates broadly to gas generating apparatus, but, inasmuch as certain advantages characteristic of the invention prominently appear in its more intense aspect as an acetylene gas buoy, it will be conducive to a more complete disclosure to detail such embodiment thereof.

This invention has in view, among other objects, the provision of an apparatus of the above-named nature in which two dissimilar substances may be brought together under conditions setting up a mutual decomposition with a concomitant production of gas, and this uniformly and at predetermined rates, without requiring an unduly involved apparatus.

An object more specifically contemplated by this invention is the provision of a buoy or float adapted to be anchored on a body of water, and so constructed as to automatically generate proper quantities of gas, such as acetylene, for maintaining a beacon light.

Another object is to devise an apparatus of the foregoing character especially adapted for handling calcium carbide, and having facilities for replacing exhausted carbide at predetermined intervals.

In general, this invention seeks to provide a device of the nature disclosed, which, from a practical operative standpoint, will possess a high degree of efficiency and durability, and which, structurally considered, will be of the greatest possible simplicity, being composed of but few parts, all of which may be manufactured at a minimum of cost and all of which are so correlated as to be capable of being very readily assembled to accomplish the purposes intended.

Other objects and advantages will be in part obvious from the annexed drawings and

in part pointed out in the following description.

In order that this invention may be more fully disclosed and made comprehensible to others skilled in its related parts, drawings illustrating one of the many possible utilizations of the same are annexed as part of this disclosure, though obviously the underlying features of this invention may be otherwise applied by modifications deducible from this disclosure and accordingly comprehended within the intended scope of the annexed claims.

In the appended drawings like characters of reference denote corresponding parts, throughout all the views of which—

Figure 1 is a sectional side elevation of an acetylene gas buoy embodying the features of this invention and arranged for practical operative use; Fig. 2 is an enlarged view of the lower portion of the apparatus of Fig. 1, showing in greater detail the carbide containing means, and the valve and pipe connections; and Fig. 3 is a section taken along line 3—3 of Fig. 2.

Continuing now, by way of a more detailed description, making occasional reference to the annexed drawings as indicated by the numerals, the body or float of this apparatus is indicated by 1 and, as will be apparent, may assume diverse shapes. Uprising from the dome of the body 1 may be a beacon supporting tower or frame 2 of structural iron or other material and construction. The interior of the body 1 forms a large chamber for the storage of gas, which is withdrawn therefrom through an aperture 3, preferably at its upper end. A pipe 4 leads to the buoy lantern or beacon, and, for the purpose of regulating the flow of gas, a valve 5 may be interposed.

The gas generating features of this invention may now be set forth. The lower part of the body portion 1 is elongated and contracted, and to this end may consist of a plurality of detachable tubular sections 6 and 7. These sections may be bolted together at their ends by means of their abutting annular flanges, and the lower extremity of the underlying section 7 may be provided with an end cap 8, detachably positioned by

means of bolts 9, or their equivalents. The lower section 7 is to serve as a receptacle or container for a series of carbid cartridges 10, each of which is provided with a series of 5 perforations 11 to enable the water to enter the same when at the level of such perforations, thereby producing a chemical reaction between the calcium carbid and the water, with the resultant production of acetylene 10 gas on the one hand and calcium hydrate on the other. The admission of water to the receptacle 7 containing the carbid cartridges takes place through a water inlet pipe 12, located at any desired point below the 15 surface of the water, in accordance with the pressure desired in the buoy. The quantity of water admitted through the inlet 12 is controlled by a valve 13 actuated by a diaphragm, which, in turn, operates in proportion 20 to the pressure of the gas in the storage chamber of the body 1. After passing through the valve 13, the water emerges through a pipe 14, which leads into the upper end of a tube 15. This tube conducts the 25 water directly to the bottom of the cylinder 7 and admits such water to the same through the apertures 16. The water in rising soon fills up to the perforations in the lower carbid cartridge and in consequence enters such 30 cartridge and comes in contact with the calcium carbid, thereby spontaneously generating acetylene gas. This gas, of course, rises in the space around the cartridges and passes upwardly into the storage chamber of the 35 body 1 through a pipe 17, which extends well above the maximum water line, that is to say, it terminates at a point 18 near the dome of the interior of the body 1. As will be obvious, the acetylene gas in accumulating 40 in the storage chamber of the body 1 continually increases in pressure, which is communicated to the water inlet valve 13, so as to vary the rate of admission of the water in inverse proportion to the increase in pressure 45 of the gas in the buoy chamber. It may here be stated that the diaphragm 20 is interposed between the sections 6 and 7, and the pipe 17 is screw-threaded through such diaphragm, as is also the pipe 22, which 50 leads through the body 1 to the outside atmosphere. The valve 13 is screwed to the diaphragm 20 so as to provide a subchamber 23 which, by virtue of pipe 22, always remains at atmospheric pressure, whereas the 55 other portions of the apparatus inclosed within the body 1 remain at the greater pressure provided by the gas stored in the chamber. Here it is to be observed that this latter pressure corresponds to the depth of the 60 inlet 12 below the surface of the water. In practice, it has been found that a submergence of the inlet 12 below the surface of the water a distance corresponding to a pressure of four pounds meets all practical require-

ments. The withdrawal of gas to be burned 65 in the beacon necessarily tends to produce a diminution in the pressure of the gas within the chamber of the body. In consequence of this reduced pressure, which is freely communicated to the underside of a flexible or 70 movable diaphragm in the valve 13 (the other side of such movable member being subjected to the lower atmospheric pressure by virtue of pipe 22) a movement of the valve will take place, thus augmenting the flow of 75 water through the inlet 12 into the section 7 supplied with carbid. In consequence of this additional supply of water, a further reaction between the carbid and such water will continue, thus generating fresh supplies 80 of gas. This gas will, in turn, pass into the storage chamber, thereby increasing the pressure in the same, and the effect of this will be to communicate such pressure through the pipe 19 and shut off or diminish the 85 further supply of water. As will be evident, this series of operations will take place evenly and at a rate corresponding to the withdrawal of gas from the storage chamber of 90 the body 1. Ultimately, the lower chamber 95 of the receptacle 7 will become filled with water, which will rise in pipes 18 and 19 until it reaches the level of the water surrounding the buoy. At this point it will be necessary to replenish the stock of calcium carbid, which may be done by lifting the buoy from the water, by removing cap 8 and refilling the receptacle 7 with new cartridges, and then, after replacing the cap 8, the buoy 100 is once more ready for service.

It will be seen that I have succeeded in devising an apparatus well adapted to achieve the ends in view. The design of the parts is such that many of them, such, for example, as the lower cylindrical members 6 and 7 105 and associated parts, may be conveniently attached to the gas buoys now commonly in use, thus without material expense converting the same into acetylene gas buoys.

As many changes could be made in the 110 above construction and many apparently widely different embodiments of this invention could be made without departing from the scope thereof, it is intended that all matter contained in the above description or 115 shown in the accompanying drawings shall be interpreted as illustrative and not in a limiting sense. It is also to be understood that the language used in the following 120 claims is intended to cover all of the generic and specific features of the invention herein described and all statements of the scope of the invention which, as a matter of language, might be said to fall therebetween.

Having described my invention, what I 125 claim as new and desire to secure by Letters Patent is:

1. In a device of the nature disclosed,

- comprising in combination, a receptacle containing calcium carbid, means for maintaining said receptacle in submerged relation with a body of water, an inlet continuously communicating with the water in which the receptacle is submerged for enabling water to enter said receptacle to react with said carbid, a valve controlling said inlet, and differential means operated jointly by atmospheric pressure, and the excess pressure of generated gas for operating said valve. 10
2. In a device of the nature disclosed, comprising in combination, a hollow float, an elongated submerged receptacle secured to a submerged portion of said float, a portion of said receptacle being adapted to contain calcium carbid, a water inlet opening into said carbid containing portion of said receptacle and continuously communicating with the water in which the receptacle is submerged, a differential valve controlling the inflow of water through said inlet, a pipe connected to said valve, whereby the latter may receive normal atmospheric pressure, and another pipe leading to said valve, whereby the same may receive gas pressure and undergo differential movement. 20
3. In a device of the nature disclosed, comprising in combination, a hollow float forming a storage chamber, a closed submerged receptacle detachably secured to a submerged portion of said float, said receptacle being adapted to contain calcium carbid, a valve establishing communication between the interior of said receptacle and the water in which it is submerged, means for admitting generated gas to said storage chamber, and means differentially actuated by the pressure of said stored gas and the normal atmospheric pressure for actuating said valve to control the inlet of water. 30
4. In a device of the nature described, in combination, a float comprising a chamber for the storage of gas, said chamber being at all times free from water, a submerged receptacle carried by said float and adapted to contain calcium carbid, a connection between said receptacle and said chamber for allowing the generated gas to pass from the former to the latter, a water inlet for said receptacle communicating with the water within which it is submerged, and automatically operating means for controlling the flow of water through said inlet. 40
5. In a device of the nature disclosed, comprising in combination, a float adapted to be placed in a body of water, an elongated receptacle depending from a submerged portion thereof, a conduit having an imperforate intermediate portion extending from the bottom of said receptacle to an upper portion thereof, a plurality of perforate carbid containers arranged in superposed series within said receptacle, and means differentially actuated by the pressure of the generated gas and normal atmospheric pressure for admitting water from the body of water in which the float is placed into the upper end of said conduit, whereby said water may be delivered into the lower end of said receptacle and rise to successively decompose the carbid in said containers. 65
6. In a device of the nature disclosed, comprising in combination, a float, an elongated receptacle depending from a submerged portion of said float, a plurality of perforate carbid containers rising in superposed series from the bottom of said receptacle, and a valve communicating with the water externally of said float for admitting water directly into a lower portion of said receptacle, and means differentially actuated by the pressure of stored gas and the normal atmospheric pressure for controlling the said valve. 75
7. In a device of the nature disclosed, comprising in combination, a float, an elongated receptacle depending from a submerged portion of said float, a partition interposed between the interior of said receptacle and the chamber in said float, a pipe passing tightly through said partition and rising into the chamber of said float to a point above the normal water line, whereby gas, but not water, may flow from said submerged receptacle into said storage chamber, and means differentially controlled by the pressure of gas in said storage chamber and the normal atmospheric pressure for admitting water into said receptacle. 85
8. In a device of the nature disclosed, comprising in combination, a float having a gas storage chamber, a receptacle depending from a submerged portion of said float, a partition interposed between the interior of said receptacle and said storage chamber, a pipe leading from the interior of said receptacle tightly through said partition and terminating in said storage chamber above the water line of said float, a valve arranged in said receptacle underlying said partition, a pipe leading from said valve tightly through said partition and terminating in said storage chamber above the water line thereof, and a pipe leading from said valve to a point in the atmosphere above the water line, means in said valve for controlling the inlet of water according to the differential pressure existing between the stored gas and the normal atmospheric pressure, and a superposed series of perforate carbid containers arranged in 100 said receptacle. 110
9. In a device of the nature disclosed, comprising, in combination, a receptacle containing calcium carbid, means for maintaining said receptacle in buoyantly submerged relation with a body of water, an inlet for en- 125

abling water to enter said receptacle, and an automatically operating valve for controlling the flow of water through said inlet.

10. In combination, a buoy provided with a submerged portion adapted to contain calcium carbide, a conduit communicating with the water exterior said buoy and leading into said submerged portion, and an automatic-

ally operating valve for controlling the flow of water through said conduit.

10
In testimony whereof I affix my signature, in the presence of two witnesses.
